TRAFFIC GUIDE

Michael A. Mulieri, New York, N. Y.

Application April 10, 1937, Serial No. 136,061

1 Claim. (Cl. 94—1.5)

This invention relates to traffic guides of the character which project above the surface of the pavement to physically divide a street or highway into lanes appropriate for traffic moving in opposite directions, or to divert traffic to either side of safety zones, trolley stations, etc. Heretofore guides or guards of this type, as distinguished from mere markers, have been of two classes, namely: low, flat, or inclined structures which may be safely crossed; and comparatively high, substantial barriers calculated to prevent vehicles from transgressing the boundaries they define.

Constructions of the first class are primarily markers and depend to a large degree for their effectiveness upon the care and responsibility of the motorists and the penalties exacted for violations of the traffic regulations. The second class of guards are usually constructed with straight side walls which present a hazard to traffic, endangering vehicles which may inadvertently swerve against them. Moreover, the side walls of such barriers ordinarily afford sufficient traction for the vehicle to pass over them, so that they fail in their primary purpose in that the transgressing vehicle ultimately crosses into the adjacent lane of traffic where it is in imminent danger of being struck by other cars to which it immediately becomes a menace.

It is a principal object of this invention, therefore, to provide an improved traffic separator or guide having its side walls so formed that it is less likely to afford sufficient traction surface for the wheel of a swerving vehicle to climb over it, but will tend to guide an obliquely impinging wheel back on the proper course without subjecting the vehicle to undue shock or damage.

Another object is to provide an improved structure of light weight and great strength which will occupy a minimum of space in the roadway.

A further object is to provide an improved guide of this character which may be readily and economically manufactured and installed in sections of convenient lengths, certain or all of said sections having end wall portions disposed at an oblique angle to the surface of the pavement to provide display surfaces for traffic directions, warnings, or other markings, in planes normally within the view of the motorist, so that such markings or directions may be conveniently observed at substantial distances and without requiring the motorist to divert his attention from the roadway. A further object is to provide such inclined end portions at angles such that a wheel driven against the end of a section may easily ride up onto the top of the device and the vehicle will

not be subjected to damage or undue shock or strain.

Other and further objects will appear from the following specification.

Referring to the drawings which form a part of this specification:

Figure 1 is a plan view of a short traffic guide section embodying the features of my invention.

Figure 2 is a side elevation of the device embedded in the pavement, the pavement being shown in cross section.

Figure 3 is an end elevation of the guide embedded in the pavement as shown in Figure 2.

Figure 4 is a plan view of a highway or street adjacent an intersection, showing a plurality of my guide sections dividing the highway longitudinally.

Figure 5 is a fragmental end elevation of a section appropriately marked for the use illustrated in Figure 4.

Figure 6 is a plan view of a street or highway having trolley car tracks extending centrally thereof and a plurality of my improved guide sections arranged parallel to divert traffic to either side of a trolley car station.

Figure 7 is a view similar to Figure 5 showing a section appropriately marked for the use illustrated in Figure 6.

As shown in Figures 1 to 3, each section of my improved traffic guide consists of a narrow solid body or block 9 of cast iron, or other strong material, having a flanged base 10, the side walls of the base tapering upwardly so that when embedded in the pavement 25 the base presents sides 11—11 of substantial area against the paving material in the relation of an inverted keystone, thereby firmly anchoring the device in the pavement.

The top surface 12 is preferably flat and painted white to increase its visibility and its side margins 40 are beveled or rounded off at 13—13. Figures 1—3 and 7 show the top margins beveled while Figure 5 illustrates the rounded edge margins. The side walls 14—14 are recessed from closely adjacent the beveled or rounded margins of the top to the base 10, thus defining narrow longitudinal side flanges 15—15, the side walls preferably receding gradually so that the sides present concave or arched surfaces. Formed in this manner the device is comparatively light and economical of material and the lightness and economy are obtained without sacrificing materially the strength essential for its purposes.

The upper portions at either or both ends of each section are inclined at an angle of about 55

forty-five degrees, thereby providing upwardly and outwardly facing display areas 16 for traffic markings, such as the direction indicators shown. Such markings are preferably represented in materials of contrasting color having high light reflecting properties sunken or recessed in the display surfaces.

- 5 Each section 9 is preferably of an over-all height of about twelve inches, of which approximately four or five inches, including the base 10, is embedded in the pavement. The sections may be of any convenient lengths and for the purposes illustrated in Figure 4 I have found that lengths of about five feet are well suited. Shorter sections, such as illustrated in Figures 1-3, will be 10 found useful for the junctions of forked roads or for defining and bounding the limits of safety zones, or trolley car stations as illustrated in Figure 6.
- 15 20 Referring particularly to Figure 4, the sections are embedded in the pavement 25 in end to end relation intermediate the side walks 26-26. The sections may be placed in close abutment or with a space between 27 to permit drainage. They may also be made in forms curved to conform 25 to the curves in the road or highway, if desired, although the use of straight sections of moderate length can usually be satisfactorily arranged slightly out of alignment to accommodate 30 all ordinary road curvatures.

35 Installations on new roads will require only that the sections be set in position on the road foundation preliminary to the emplacement of the surface paving. Installations on existing streets or highways will only require cutting a small section of the road surface due to the narrowness of the sections.

40 Installed on the road in the manner illustrated in Figure 4, the sections afford a substantially continuous guard or guide calculated to prevent violation of various traffic regulations, preventing automobiles from going out of line into the wrong side of the road, preventing U turns, and discouraging speeding. Being narrow, my improved 45 guide occupies a minimum of space which might otherwise be made available to traffic and, being of substantial height above the pavement, pedestrians are discouraged from attempting crossings except at proper intersections.

50 Aside from the lightness, economy, and strength of the sections and the space economy they obtain, their peculiar shape obtains important advantages. For instance, if the wheel 30 of an automobile should impinge endwise against an 55 endmost section, as indicated in Figure 2, the inclination of the display surfaces, being tangential to the periphery of the wheel, will afford

traction for it and permit the wheel to roll up onto the top surface of the section without damage or undue shock. If a car running substantially parallel to the guard swerves against it, the tire of the car wheel will obliquely impinge only 5 against one of the narrow flanges 15, as indicated in Figure 3, and since the flange is very narrow, insufficient traction is afforded for the wheel to climb over the guard and the wheel is caused to pivot back on a proper course. When the device 10 is made of metal, such as cast iron, or other smooth material, and particularly when the narrow flanges 15 are rounded as shown in Figure 5, the tire of a wheel riding against the guard will be subjected to very little abrasion or wear. 15

If the side walls as well as the top are painted, tires cannot ride against the recessed areas of the side walls and therefore will not wear away the paint. The display surfaces 16 at the ends of the sections are faced in the normal plane of 20 vision of the vehicle operators and may be marked to give ample and frequent warnings or directions which will be readable at considerable distances without requiring that the motorist divert his attention from the road. 25

Short sections may be conveniently and effectively employed to define or bound the limits of safety zones or trolley car stations. A plurality of short parallel sections arranged for the latter use are illustrated in Figure 6 in which 25' indicates the roadway, 26'-26' the sidewalks, and the trolley car tracks are designated at 28. On the near side of the intersection, the sections 9-9 30 protect the trolley station 29 and their outwardly facing display surfaces are appropriately marked 35 as shown in Figure 7. Other and further arrangements and uses will occur to those skilled in the art to which this invention relates.

Having thus described my invention, I claim:

40 In a roadway, a traffic guide comprising a plurality of oblong sections arranged end to end, each of said sections having a base portion embedded in the roadway and an integral portion projecting above the surface of the roadway a distance less than the radius of a road wheel, a narrow 45 outwardly extending flange at opposite sides of the top of each section, the side walls of each section being recessive between said flanges and the surface of the roadway, whereby a vehicle wheel impinging against a side of the guide can 50 abut only against said flanges, upper end portions of certain of said sections being beveled, the slope of said beveled portions being substantially tangential to the periphery of a vehicle road wheel. 55

MICHAEL A. MULIERI.
